LAWN SPRINKLER

Jesse P. Hubbell, Fanwood, N. J.

Application October 20, 1932, Serial No. 638,755

3 Claims. (Cl. 299—18)

The general object of the present invention is to provide improved apparatus for sprinkling lawns and analogous purposes. More specific objects of the invention are to provide improvements in sprinkler head or spray device construction, especially adapted for use in a sprinkling system characterized by the relative ease and uniformity with which a large area can be sprinkled with apparatus which may consist essentially of a suitable length of flexible hose such as ordinary garden hose and a few sprinkling heads or spray devices of simple construction and relatively inexpensive.

My improved sprinkling head or spray device is characterized from the operative standpoint by its capacity for delivering a spray discharge which will distribute water with desirable uniformity over a horizontal area which may be described as an annular arc, i. e. a sector portion of an annulus, and which is characterized from the mechanical standpoint by its simplicity and ruggedness and inherent capacity for production at relatively low cost.

In the above mentioned sprinkling system, I employ a plurality of spray devices, each delivering a spray discharge of the above mentioned annular arc from, and all connected at different points along the length of a common flexible water supply pipe or hose and normally so relatively spaced that the areas simultaneously wet by the different spray devices merge at their ends to form an undulating zone or strip, at one side of, and generally parallel in length to the straight, or approximately straight, line along spaced apart points of which the different spray devices are then located. When sufficient water has been sprayed upon one such zone, the spray devices may be adjusted to new positions in which they collectively wet a zone parallel to and merging at one edge with one edge of the zone previously wet, and in making such adjustments it is unnecessary to interrupt the discharge of water through different spray devices, since the user making the adjustments may remain at the side of the hose away from which the sprays are directed. Furthermore, with the length of the hose section between each adjacent pair of spray devices suitably in excess of the normal operating distances between the latter, sufficient slack in the hose is provided to permit the different spray devices connected to the hose to be so adjusted one at a time.

The various features of novelty which characterize my invention are pointed out with particularity in the claims annexed to and forming

a part of this specification. For a better understanding of the invention, however, and the advantages possessed by it reference should be had to the accompanying drawing and descriptive matter in which I have illustrated and described a preferred embodiment of the invention.

Of the drawing:

Fig. 1 is a diagrammatic plan view illustrating my improved sprinkling system:

Fig. 2 is a sectional elevation of one of the 10 spray devices shown in Fig. 1;

Fig. 3 is a section on the line 3—3 of Fig. 2;

Fig. 4 is a section on the line 4—4 of Fig. 2; and

Fig. 5 is an elevation of another spray device shown in Fig. 1.

The sprinkling apparatus shown in Fig. 1 comprises a flexible hose A, which may be ordinary garden hose, and spray devices B, B' and B² supplied with water by the hose A. The device B is connected to the hose A at the discharge end of 20 the latter and the spray devices B' and B² are connected to the hose at suitably spaced points along the length of the latter. In the normal contemplated use of the apparatus illustrated in Fig. 1 the spray device B' is located at approximately the mid-point of the straight line connecting the spray devices B and B². With their positions shown in Fig. 1, the spray devices B, B' and B² are adapted to simultaneously sprinkle ground areas C, C' and C², respectively. Those 30 areas are similar in form and dimensions, each having curved inner and outer edges C³ and C⁴ each approximately an arc of 180° about the corresponding spray device. The ends of the arc shaped areas C, C' and C² extend approximately along the line along which the devices B, B' and B² are located. As shown at their adjacent ends small portions C⁴ of the adjacent areas C, C' and C² overlap and the three areas 35 collectively form a sprinkling zone or area of undulating form at one side of, and generally parallel to the line along which the sprays are located.

In Fig. 1 the areas CA, CA', and CA² represent areas which may be respectively sprinkled by the 45 devices B, B' and B² when the latter are similarly adjusted transversely of the line along which they are shown in Fig. 1, to the positions indicated by the points b, b' and b², respectively. The zone or area collectively formed by the areas CA, CA' and 50 CA² is similar in form to the zone comprising the areas C, C' and C². As shown in Fig. 1 small portions C⁵ of the two zones overlap. The overlapping portions C⁴ and C⁵ receive more water than the remaining portions of the ground sprinkled, 55

but the resultant departure from uniformity in sprinkling is small because of the relatively small aggregate area of the overlapping portions, and is insignificant in comparison with the area receiving more than the amount of water required with ordinary sprinkling systems operated to insure that no portion of the ground sprinkled receives too little water.

By making the lengths of the hose sections between the spray devices B' and the spray devices B and B^2 slightly greater than the actual distances between the spray device B' and each of the other spray devices when positioned for use as shown in Fig. 1, it is possible to move any one of the three spray devices between its position shown in Fig. 1 and the corresponding position b , b' or b^2 without simultaneously shifting either of the other two spray devices. In the ordinary use of the apparatus shown in Fig. 1 in spraying a surface area including sections C , C' , C^2 , CA , CA' and CA^2 , the spray devices will be adjusted in the direction away from and not toward the zone previously sprinkled. In other words the area including the section areas CA , CA' and CA^2 will be sprinkled before the areas C , C' and C^2 are sprinkled. With such order of sprinkling, the user may stay at the dry side of the hose while shifting the positions of the spray devices and may shift the latter without interrupting the spray action and without objectionable wetting by the sprays delivered.

The contemplated use of the apparatus shown in Fig. 1 thus permits of the easy and rapid sprinkling of an extended area with a relatively small and insignificant amount of overlapping and consequent lack of uniformity in wetting the individual areas sprinkled by the individual spray devices. It hardly needs to be pointed out that the number of spraying devices served by a single hose may be varied as conditions require. Except in the case of an unusually small lawn, at least two spray devices will be used, and to insure adequate water pressure at each spray device, it is ordinarily preferable to connect not more than three spray devices, or four spray devices at the most, to a single supply hose. In sprinkling a lawn of relatively large area, side by side strip-like portions thereof may well be successively sprinkled, the sprinkling operation for each strip consisting in the successive sprinkling of successive zone portions like those formed by the sections C , C' and C^2 , and the sections CA , CA' and CA^2 of Fig. 1.

The spray devices B , B' and B^2 may be of identical construction in respect to their spraying provisions, and advantageously embody the special features of construction and arrangement illustrated in Figs. 2, 3 and 4. The spraying devices B' and B^2 may each be an exact counterpart of the other, but the body portion of the spray device B may well be different in form from the body portions of the spray device B' and B^2 , since the body of each of the devices B' and B^2 is interposed between two hose sections, whereas the device B is connected to the end of a single hose section only.

The spray device B' in the form shown in Figs. 2, 3 and 4, comprises a body portion in the form of an inverted T having a threaded socket B^3 at one end of its horizontal portion internally threaded to receive a hose coupling spigot or externally threaded part of standard form, and having the opposite end B^4 of its horizontal portion externally threaded to enter a hose coupling socket of standard form. The uprising tubular outlet portion B^5 of the body is externally thread-

ed to receive a cap member D which forms the supporting base member of the spray nozzle proper. The latter comprises a body member E which extends through an opening D' in the otherwise closed top wall of the member D . At its lower end the member E is formed with a radial flange E' which abuts against the underside of the top wall of the member D at the margin of the opening D' . To permit angular adjustment of the nozzle member E relative to the member D , the opening D' is made circular in cross-section, and the portion of the member E within the opening is shaped to fit within the peripheral wall of the opening.

The member E is formed with a vertical water passage or chamber E^2 which in cross-section is in the form of a section of an arc, preferably and as shown, the section being approximately semi-circular. The upper edge E^3 of the cylindrical wall portion of the member E at the convex side of the passage E^2 is beveled to form the underside of an inclined arc shaped discharge nozzle orifice E^4 , the opposite wall of which is formed by the correspondingly beveled surface e' of a plate-like member e which extends across the top of the channel E^2 and is secured against the upper end of the portion of the member at the concave side of the channel E^2 . As shown the member e comprises an integral down turned portion e^2 and an integral portion e^3 projecting horizontally away from the lower end of the portion e^2 . The portion e^2 fits against the adjacent flat outer side of the member E , and the portion e^3 cooperates with the flange E' to hold the member E in place in the opening D' when the nozzle structure is assembled. The members E and e may be secured together in any suitable manner. When those members are die-cast, as they well may be, the connection between the members may advantageously comprise a tapered socket E^5 in the member E receiving and frictionally holding an integral tapered projection e^4 from the underside of the upper portion of the member e , which is forced into the socket E^5 . Ordinarily, a yielding washer F is mounted in the cap member D between the flange E' and the upper end of the spigot outlet B^3 on which the nozzle is mounted.

With a nozzle having its water channel E^2 and discharge orifice E^4 formed as described, the horizontal area sprayed in any one setting of the orifice will be substantially of the form of one of the sections, C , C' , etc., of Fig. 1. With the concave and convex walls of the channel E^2 extending circularly about a vertical axis as shown in Fig. 4, the curved edges of the horizontal area sprayed will be slightly more convex than are truly circular arcs. In other words, water will be thrown farther by the spray device adjacent the center or crown of the section wetted than adjacent the ends of the latter, so that the area wetted is a section of an annulus which is elliptical rather than circular. The water distribution over the section sprayed will be quite uniform provided the end walls E^7 of the curved channel E^2 are properly shaped. I have found that to prevent excessive water discharge onto the ends of the annular arc the walls E should not extend in planes radial to the axis of the convex and concave walls of the channel E^2 but should be inclined to those planes so that in angular extent about said axis the outer convex wall exceeds the inner concave wall substantially as shown in Fig. 4. It is to be understood of course that by diminishing the angular extent of the curved walls of the channel E^2 , the arc

length of the section, C, C', C², etc., sprinkled will be correspondingly shortened. As those skilled in the art will understand, while practically all of the water discharged will fall within the confines of the section, C, C', etc., some water will be discharged on the ground adjacent but at the outer sides of said section.

The body portion of the spray member B, as shown in Fig. 5, differs from the body member 10 of the devices B' and B² in that it is of elbow form, providing a single water thoroughfare passage with a horizontal socket B⁶ internally threaded, like the socket B³ previously described, to receive a hose coupling spigot part. At its 15 upper end, the body of the spray device B terminates in an externally threaded portion B⁷ like the previously described outlet B⁵, on which the base member D of the associated nozzle is threaded. It will be apparent, however, that a body 20 like that employed in the devices B' and B², with its outlet B⁴ closed by a cap might be used as the body element of the device B in lieu of the special elbow form shown.

The proper relative spacing of the sections 25 simultaneously sprinkled by different spray devices connected to a single hose, and the proper form of the individual sections require a proper relative spacing of the devices and the proper disposition of each individual spray device. In 30 the use of the apparatus to sprinkle a flat ground area, the device B' should ordinarily be located midway between the devices B and B², and the axes of the three devices should be parallel and in most cases should be vertical, and each end 35 wall E⁷ of each spray device should be parallel to the corresponding wall E⁷ of each of the other two devices. In wetting a ground area which is continuously horizontal but undulating, it may be advantageous, however, to arrange the 40 devices so that said axes are not parallel. Some variations in the relative spacing of the devices and in the relative directions of their spray discharges may be desirable in some cases, also, to accommodate irregularities in the contour of the 45 ground sprinkled, or because of winding walks or other special characteristics of the area sprinkled.

The general direction of discharge from any 50 one spray device may obviously be varied somewhat by bodily adjustment of the spray device angularly about the axis of its water passage E². A wide adjustment of the general direction of discharge from any spray device may be made without change in the position of the body portion 55 of the device, by angular adjustment of its member E relative to said body portion. Ordinarily the last mentioned adjustment will be effected only when the water supply is interrupted so that the cap D may be readily loosened 60 to prevent the normal clamping pressure on the flange portion E' of the member E from interfering with the adjustment.

In order that each spray device, on each ad-

justment of the latter, may be accurately and easily anchored in the proper position, I advantageously provide the body of each spray device with a prong or projection B⁸ which can be pressed down into the earth to anchor the device in the ground at the proper surface point, and with the desired direction of discharge. Advantageously each prong B⁸ is in the form of a pointed steel rod having its normally upper end cast into the body of the corresponding spray 10 device.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. A spray nozzle formed with a chamber open at one end having a restricted outlet orifice at its opposite end, with said chamber of annular arc cross section and said orifice in the form of a slot opening from said chamber at the convex 30 side of the latter and the walls of said chamber connecting the convex and concave sides thereof being inclined relative to the radial planes intercepting the ends of said convex side of said chamber so that the convex side is of greater 35 angular extent than its concave side.

2. In a spray nozzle, the combination of a cap member adapted for attachment to a fluid outlet and formed with an opening in its end wall, a second member extending through said opening 40 and formed at its inner end with a flange engaging the inner side of said end wall at the margin of said opening and formed with an open ended water chamber and a third member connected to said second member and comprising 45 a portion uniting with the latter to form a restricted outlet orifice from said chamber and a second portion overlying the outer side of said end wall and thereby holding said members together.

3. In a spray nozzle, the combination with a member formed with an open ended chamber of annular arc cross section and having the convex wall of said chamber at one end of the latter beveled, of a second member comprising a plate-like portion extending across said chamber and in contact with a portion of the wall of said chamber at said one end and including a curved beveled edge cooperating with said beveled wall to form an elongated arc shaped discharge orifice leading radially and axially away from said chamber.

JESSE P. HUBBELL.
